(57) **CLAIM**

I claim the ornamental design for a score card holder, as shown and described.

DESCRIPTION

FIG. 1 is a front perspective view of a score card holder showing my new design, shown in a closed position;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front perspective view thereof, shown in partially open position; and,

FIG. 9 is a front perspective view thereof, with fully open position.
